E. F. WALDNER,
WINDOW SHADE,
APPLICATION FILED MAR. 30, 1916.

1,238,464.

Patented Aug. 28, 1917.

UNITED STATES PATENT OFFICE.

ELMER F. WALDNER, OF EUREKA, CALIFORNIA, ASSIGNOR TO ANTON HANSON, OF SAN FRANCISCO, CALIFORNIA.

WINDOW-SHADE.

1,238,464.

Specification of Letters Patent. Patented Aug. 28, 1917.

Application filed March 30, 1916. Serial No. 87,862.

To all whom it may concern:

Be it known that I, ELMER F. WALDNER, a citizen of the United States, and a resident of Eureka, county of Humboldt, and 5 State of California, have invented a new and useful Improvement in Window-Shades, of which the following is a specification.

The invention relates more particularly to vertically adjustable shades in which the 10 roller is movable toward and away from the top of the window, so that any portion of the window may be uncovered or covered by the shade as desired.

Another and more specific object of the 15 invention is to provide in an adjustable shade of this nature means whereby the roller will be rotated as the shade is being adjusted vertically.

Heretofore, when it has been desired to 20 shade the lower portion of the window and leave the upper portion uncovered, the roller has been placed at the bottom of the window and the shade string run around a roller or pulley at the top of the window so that the 25 shade may be raised and lowered.

In this construction the roller was fixed 30 against the vertical movement and therefore it was impossible to uncover the lower portion of the window without entirely winding the shade. My improved construction is superior to the one here described, 35 inasmuch as the roller is hung to rotate in the customary manner and it may be moved to any position desired in respect of the window.

The invention also aims to generally improve devices of this nature to render them more practicable, durable and commercially desirable.

40 With these and other objects in view, the invention consists in such novelty of construction, combination and arrangement of parts as will be hereinafter fully described, illustrated and claimed.

45 In the drawings:

Figure 1 is a front elevation showing my improved shade in position on a window frame.

Fig. 2 is a side or end elevation showing 50 the shade on the window frame.

Fig. 3 is a fragmentary side elevation showing one of the shade brackets and the wheel which causes the shade to rotate as it is adjusted vertically.

55 Fig. 4 is a view taken on the plane at

right angles to the plane of Fig. 3, showing the roller, the wheel, the brackets, and the wire which serves to rotate the wheel.

Fig. 5 is a side elevation of the spring drum, the casing being partly broken away 60 to show the spring, and

Fig. 6 is a transverse section on the plane of line 6—6 of Fig. 4, showing the construction of one of the guides and the manner in which the brackets are secured 65 thereto.

Referring in detail to the drawings by numerals, 1 designates as an entirety a window casing of any construction, having a top horizontal bar 2 and side bars 3, 4, to 70 which my improved shade is shown secured.

In the preferred embodiment of the invention, a pair of guides 5 and 6 are provided, said guides being rigidly secured to the window casing in spaced parallel 75 relation. Each of the guides is provided with a base portion 7 carrying an outstanding angular flange 8, as best shown in Fig. 6. The guides are mated so that the angular flanges 8 project outwardly with respect to 80 the vertical center line of the window. These guides may be made of any suitable material and may be secured in position by any desired means.

Slidable upon the flanges 8 of the guides 85 are the shade brackets or runners 9 and 10. These brackets are preferably formed or stamped from metal and are each provided with a forwardly extending flange or web 11 which is slotted as indicated at 12 in Fig. 90 3, and which is provided with a pivoted locking hook 13 to hold the roller in position as is hereinafter set forth.

On both ends of the bases of the flanges 11 are provided the hooked extensions 14 95 and 15 which extend across the outer faces of the flanges 8, then rearwardly toward the window frame, and then laterally to hook under the extensions on the flanges, as is clearly shown in Fig. 6.

The upper extensions or hooks 14 are formed with ears 15' to which are connected the cords 16 which run around the rollers or pulleys 17, secured in the brackets 18 on the upper end of the guides 5 and 6, 105 and which are connected to opposite sides of the spring drum 19 so that when the drum rotates, the cord will either be wound or unwound. As shown best is Fig. 5, the spring drum is mounted on a pivot 110

20 to which is connected one end of the spring 21, the other end of said spring being connected to the interior of the casing. This casing or drum is provided on its periphery with the double channels 22 and 23, one channel being for each of the cords 16.

5 The spring 21 is always under tension and tends to draw the brackets toward the top of the window and to lock the roller in any position, I provide a pull cord 24 which is secured at one end to the upper portion of the bracket 9 as shown clearly in Fig. 3. This cord passes through a clamping device 25, which will grip it at any point throughout its length and thereby anchor the bracket.

10 The shade 26 is carried preferably by a Hartshorn roller, the trunnion on one end of the roller being removably attached to the bracket 10, and the squared end on the other end of the roller being removably fitted into a wheel 28 which is formed on its outer face with a stud or trunnion 29 having a head 30. The trunnion passes through the slot in the flange 11 of the bracket 9 and is removably locked therein by the hook 13 as shown in Fig. 3.

15 The purpose of the wheel 28 is to turn the roller 27 and wind up or unwind the shade as the roller is moved vertically, and to cause the wheel to turn so that it will properly fulfil its object, a wire 31 is provided. This wire is secured at its upper end to the bracket 18, is looped once around the wheel 28 and is secured at its lower end to the bracket 32. The wheel is grooved in its periphery as shown in Fig. 4 and, therefore, there is no danger of the wire becoming disengaged therefrom.

20 In operation the roller may be adjusted to any position with respect to the window by either pulling upon the cord 24 or releasing the same from engagement with the clamp 25. As the roller moves vertically, it is caused to rotate by the action of the loop in the wire 31. The wheel 28 in turning the roller interferes in no way with the internal mechanism thereof including the spring, the dog and stops therefor, which being of the ordinary construction are not shown.

25 With the roller in the position of Fig. 1 of the drawings, the shade may be pulled down or raised in the ordinary way by means of the string 33, or if desired, the roller 27 may be raised or lowered by means of the spring 24, as previously described. The spring 21 is much stronger than the

60 spring in the roller so that the shade may be pulled down by the string 33 without causing the roller to descend.

65 The wheel 28 and wire 31 which cause the roller 27 to rotate when it is adjusted are of essential importance to the proper operation of a window shade of this nature, and it is desired to emphasize the fact that when the roller 27 is being raised or lowered this wheel and wire cause the roller to unwind or wind the shade 26 without substantially altering the position of its lower edge.

70 While I have shown and described the preferred embodiment of my invention, it will be understood that I do not wish to be limited to the exact construction and arrangement of parts illustrated and described, but may make such changes from time to time as may suggest themselves and as fall within the scope and spirit of this invention.

75 I claim:

1. In an adjustable window shade, a shade 80 roller, vertically adjustable brackets supporting said roller, vertical guides to which said brackets are slidably connected, means for raising and lowering said brackets, and fixed means interposed between one end of the shade roller and one of the brackets to turn the shade roller as it is being adjusted.

85 2. In an adjustable shade, a shade roller having a trunnion on one end and a squared extension on the other end, a wheel secured to said squared extension, slidable brackets for engagement with the trunnion end of the shade roller and with said wheel, a wire 90 looped around the periphery of the wheel and secured at its ends and means for raising and lowering the brackets, said wire serving to rotate the shade roller when the brackets are moved.

95 3. An adjustable window shade comprising a shade roller, a shade carried by said roller, brackets to support the roller, means for raising or lowering the brackets, a wheel fixed at one end of the roller, and a wire secured at its ends and looped around said wheel, whereby the roller is rotated when raised or lowered independently of the curtain.

100 In testimony whereof, I have hereinto set my hand at Eureka, California, this 9th day of March, 1916.

ELMER F. WALDNER.

In presence of—
BALDWIN VALE.
